UNITED STATES PATENT OFFICE

ELMER E. ALBRIGHT, OF PHILADELPHIA, PENNSYLVANIA, ASSIGNOR OF ONE-HALF
TO A. LINCOLN TAYLOR, OF HADDON HEIGHTS, NEW JERSEY

WINDOW SASH

Application filed November 1, 1929. Serial No. 404,000.

The object of the invention is to provide improvements in window sash, and particularly in that class in which each sash unit comprises main and secondary frame members, pivotally connected together so that one may be oscillated with respect to the other.

In the construction of office and similar buildings today there is an ever increasing need of a window construction which will permit the panes to be cleaned from the inside, and attempts have been made to solve this problem with varying results, but apparently little or no attention has been paid to the needs in this line of window construction in domestic establishments.

The object of the invention is therefore to provide a principle of construction, which by alteration of minor details of size and arrangement will adapt the same for use by both business buildings and residential structures, so that the regular cleaning force of the former and the housekeeper or maid of the latter can clean the outside of both the upper and lower sash of a window, as well as the inside thereof, with the utmost ease and convenience, and without necessitating that anyone shall have to lean out of or sit or stand upon, the window sill.

In addition to the foregoing, an object of the invention has been to so construct the main and secondary frames, that each improved sash as a unit operates to positively prevent the passage, either of wind when blowing in any direction whatever, or of rain and sleet when being driven at unusual angles.

With the objects of the invention thus broadly stated, the invention comprises novel details of construction and operation, which are hereinafter fully brought out in the following description, when read in conjunction with the accompanying drawings, in which Fig. 1 is a front elevation of a window comprising one embodiment of the invention; Fig. 2 is a rear view of the same; Figs. 3, 4 and 5 are sections on the lines 3—3, 4—4 and 5—5, respectively, of Fig. 2; Fig. 6 is an elevation of the main sash frame; and Fig. 7 is a corresponding view of the secondary sash frame.

Referring to the drawings, it will be assumed that the device is operatively posi-

tioned for use in the usual manner. For this purpose a wall 1 is shown as being provided with a rectangular aperture 2, within which latter is positioned the window frame. This frame is composed of the usual sash guide 3, 55 having a central bead 4 to provide spaced grooves or tracks 5 and 6, in which sash units are adapted to reciprocate. The laterally opposite limits of these tracks are defined by forward and rearward face members 7 and 8, 60 which extend freely from the guide 3 in spaced relation with each other, to provide boxes 9 for the reception of the usual sash weights (not shown), the opposite or outer sides of said boxes being closed by wall-engaging members 10, and the union or connection between said last-named members and said wall being covered by suitable moulding strips 11. 65

Each of the sash units for both the upper and lower portions of the frame is composed as before mentioned of a main and a secondary member, shown respectively in Figs. 6 and 7. The main sash member comprises a preferably rectilinear element formed of top, bottom and side pieces, 12, 13 and 14, respectively. The top piece and the upper, substantially one-half portion of each of the side pieces are extended inwardly by means of an exceedingly deep flange 15, substantially equal in 70 width to the corresponding portions of the top and side pieces 16 and 17 of the secondary sash member shown in Fig. 7, said latter being bridged at their lower ends by a bottom piece 18, and all co-operating to support the 75 usual glass pane 19.

The lower, substantially one-half portion of the side pieces 14 of said main sash member are cut away at 20, to provide flanges 21 which are connected at their lower ends by 80 the bottom piece 13, of similar thickness. Said cut away regions are thus adapted to receive laterally extending flanges 22, carried by the lower portions of the side pieces 17, while a flange 23 carried by the bottom piece 18 of 85 said secondary sash normally lies snugly and flat against the bottom piece 13 of said main sash, as shown in Figs. 3, 4 and 5, the corresponding top, side and bottom pieces of said main and secondary sashes co-operating to 90 95 100

insure against the passage of rain, sleet and wind. These sashes are pivotally connected together by any suitable form of hinge, such as the strap hinge 24, having their axes level with the union of the flanges 15 with the cut away portions 20, so that swinging the secondary sash upon the main sash removes the former freely from alignment with the latter, as the former enters its vertical reversed position.

With such a construction, it is obvious that after the secondary sash has been reversed for cleaning, replacement of the pane, or otherwise as may be desired, its weight operates to start its return movement towards normal position, whence it can be manually shifted at will after releasing any suitable form of latch, which in the present instance has been illustrated as comprising a spring-pressed pin 25 of well-known type, since such a pin when used in the upper of said sash units is out of the path of reciprocation of the lower unit, and when used in the lower unit is out of the way of shades or other hangings or decorations which may be present.

Furthermore, by using a hinge support of the type here illustrated it is obvious that, as the secondary sash approaches its reversed position, it correspondingly approaches a condition in which the friction between the adjacent sides of the sash sections becomes a minimum. In the case of certain other sash constructions, in which the axis of oscillation passes thru a transversely central portion thereof, the friction between the sash members beginning with normal position decreases towards a horizontal position, after which the friction again increases at the same rate, due to the normal lower portion of the secondary sash again entering the space between the sides of the main sash. In the present case, however, this lower secondary sash portion, after being once removed from within the main sash, does not again enter the latter as it approaches its reversed position.

Having thus described my invention, what I claim and desire to protect by Letters Patent of the United States is:—

1. A window sash, comprising a closed rectangular main member, the upper portion of which is provided with an integral marginal flange and the lower portion of which is provided with a marginal cutaway portion said flange and cutaway portions upon each side of said first member terminating in substantial alignment with each other, and a secondary sash member pivotally mounted in said member, with its upper portion of substantially the same width and normally lying against said flange, while its lower portion normally lies within said cutaway portion, and the lower portion of said secondary member being provided with an integral flange normally extending across substan-

tially the full extent of the bottom of said main member.

2. A window sash, comprising a closed rectangular main member, the upper portion of which is provided with an integral marginal flange and the lower portion of which is provided with a marginal cutaway portion said flange and cutaway portions upon each side of said first member terminating in substantial alignment with each other, and a secondary sash member pivotally mounted in said member, with its upper portion of substantially the same width and normally lying against said flange, and the lower portion of said secondary member being provided with an integral flange at the sides normally lying in said cutaway portion and at the bottom lying across the corresponding portion of said main member.

In testimony whereof I have affixed my signature.

ELMER E. ALBRIGHT.
